UNITED STATES PATENT OFFICE.

CHARLES A. NELSON, OF UTICA, NEW YORK, ASSIGNOR TO SAVAGE ARMS COMPANY,
OF UTICA, NEW YORK, A CORPORATION OF NEW YORK.

FIREARM.

1,168,024.

Specification of Letters Patent. Patented Jan. 11, 1916.

Application filed June 22, 1914. Serial No. 346,457.

To all whom it may concern:

Be it known that I, CHARLES A. NELSON, a citizen of the United States, residing at Utica, in the county of Oneida and State 5 of New York, have invented certain new and useful Improvements in Firearms, of which the following is a specification.

This invention relates to guns and particularly to guns of the automatic type, and 10 it consists in improvements in certain parts of such guns, to wit, the so-called "grip-safety" mechanism, the means for locking back the breech-bolt when the last cartridge has been fired so as to indicate that 15 the magazine is empty, the means for preventing double-firing, and the magazine catch, designed particularly to simplify the construction and reduce the cost of manufacture, facilitate assembling and disassembly 20 of the parts, increase the element of safety in the handling of the gun, and post the user at all times as to the condition of the gun.

The invention will be found fully illustrated in the accompanying drawings, 25 wherein,

Figure 1 is a left side elevation of the improved gun, partly in section; Fig. 2 is a right side elevation, the breech-bolt being 30 locked back; Fig. 3 is a fragmentary right side elevation, illustrating particularly the means for locking back the breech-bolt; Fig. 4 is a plan of the frame, with the breech-bolt removed; Fig. 5 and Fig. 6 details illustrative of a modification of said means; 35 Figs. 7 to 10, inclusive, details illustrative of the "grip-safety" means; and, Fig. 11 a front fragmentary elevation of the grip.

Except as hereinafter indicated the following parts of the gun shown in said drawings are or may be all substantially the same as the corresponding parts of the gun set forth in the Searle Patent No. 936,369, to wit: the frame *a* having the depending grip- 40 forming portion *a'*, the sliding breech-bolt *b* having the removable breech-plug *c* containing the firing pin (not shown), the hammer *d* and the sear *e*, the barrel *f*, the spring *g* for returning the breech-bolt after recoil, 45 the sear trip (or trigger and sear connector) *h*, the trigger *i*, the magazine *j* and its spring-elevated platform *k*, and the magazine catch *l*. 50

For preventing double-firing in the present case the sear trip *h* has a rigid toe *h'* 55 which, when a pull on the trigger brings it against the vertical face of a fixed shoulder *h''* on the gun frame and this results in the discharge of the arm and is followed by the depression of the sear-trip under the wiping 60 action of the rearwardly sliding breech-bolt, snaps under the shoulder and locks down the sear-trip out of the path of the (cocked) sear in the ensuing return of the breech-bolt under pressure of spring *g*. This construction 65 simplifies the sear trip, insures much greater reliability of the action thereof and makes it better adapted to withstand wear and tear, it being noted that the elasticity of the flesh of the user's finger affords the 70 necessary impetus to the sear trip to cause it to catch under the shoulder *h''*.

In the improved grip safety mechanism, a lever *m* at the back of, and shaped to conform with the contour of, portion *a'* of the 75 gun frame to form therewith the grip is fulcrumed on a transverse pin *n* in an opening *o*, its outward movement being limited by contact of a lug *p* at its upper end with the back wall of the portion *a'*. Another lever, 80 *q*, having a horizontal loop-shaped portion *q'* embracing the magazine and a depending angular leg *q''* formed with the knee *q'''*, is fulcrumed on the transverse pin *s*, its forward end having a lug which (marked 85 *t*) bears down on the surface *u* of the frame on which the trigger slides, abutting the trigger and so normally preventing its rearward movement. The lever *m* receives the contact of the knee *q'''* on its (hollow) inner side. The parts are normally held in 90 the positions described by a spiral spring *v* coiled around a sleeve *w* on pin *n* and having one end engaged in the frame and the other bearing against the forward side 95 of leg *q''* of lever *q*. The loop-shaped portion of lever *q* contacts with the sides of the magazine cavity of the frame, so that side- 100 wise movement of said lever is prevented. To similarly preserve the lever *m* against lost-motion I provide its upper end with the slotted jaws *m'* which fit nicely between and in contact with the fulcrum portions *q''''* of 105 the lever *q*, the slots of said jaws receiving the pin *s*. When the gun is properly gripped in the act of pulling the trigger the inciden-

tal forward pressure on lever *m* obviously elevates the lug *t* on lever *q* out of the path of rearward movement of the trigger, spring *v* returning the parts to their normal position when the grip is relaxed.

In the right side of the frame, under the breech-bolt, is an upwardly open elongated longitudinally extending housing or groove *x* which enters the magazine cavity at the 10 rear and has an aperture *x'* leading to its front end. A bar or lever *y* has a knee *y'* on which it rests, in a manner adapting it to tilt, on the bottom of this groove or housing; the top of the bar *y* slopes toward 15 each end from a point near the middle thereof, where it is adapted to have a fulcrum on the under side of the breech-bolt, which, when in place, confines the bar in said groove. The forward end of the bar, kept 20 normally uplifted by the spring *z*, has a finger-piece *2*, and its rear end, which overlies the magazine platform and is adapted to be elevated thereby as soon as the last cartridge is withdrawn from the magazine, 25 has a toe *3* adapted to enter a locking notch *4* in the under side of the breech bolt upon rearward movement incident to firing the last cartridge, thus locking the breech-bolt in an abnormal position and so signifying 30 that the magazine is empty; to release the breech-bolt, having replaced the empty magazine with a filled one, the operator presses upwardly with his trigger finger against the finger piece *2*, which protrudes through 35 aperture *x'*. The front ends of the housing and bar are formed rearwardly inclined, as at *x'' y''*, and the bar has a lateral pin *5* received in a forwardly inclined groove *6* in one side of the housing *x*. With this construction, due to the convergence of the surface *x''* and groove *6*, the bar cannot be removed except by holding down its forward end and elevating its rearward end, in which manner it may be removed readily. In the 40 present instance, the forward thrust of the bar under pressure of the breech-bolt is assumed by the pin *5* engaging the forward side of the groove *6*.

In Figs. 5 and 6 the construction is substantially the same excepting that the front end of the bar, *y* contacts with the front end of the housing *x* on assuming the thrust of the breech-bolt and that a spring *7* carried by the bar and held compressed between 45 the same at one side of the housing serves both to retain the bar in the position to which it is manually rocked (so long as the upward pressure of the magazine platform is absent) and to keep the bar from being 55 dislodged when the gun is taken down.

The pin *8* affording a fulcrum for the magazine catch *l* is in the present arm loosely or revolvably mounted in the frame and has a driving fit in the magazine catch. 60 Customarily, the pin has a driving fit in the

frame, which has the objection, entirely absent in the present case, that under the vibration incident to firing the gun the pin loosens and will not remain in place.

Having thus fully described my invention, 70 what I claim as new and desire to secure by Letters Patent is:

1. The combination of the frame having a rigid overhanging shoulder, a recoiling breech bolt, a spring normally opposing recoil of the breech-bolt, a cockable firing mechanism arranged in the breech-bolt and including a sear, and a rearwardly movable means, including the connected trigger and sear trip, for transmitting releasing movement to the sear, said trip being depressible by the recoiling breech-bolt and having a rearwardly projecting toe movable with the sear trip against said shoulder and adapted to snap under the latter to lock down the depressed sear trip, and said means being unyielding, from and including the trigger to and including said toe, to compression exerted longitudinally of the gun. 80

2. In combination, the frame having a 90 downwardly projecting grip-forming portion, a firing mechanism including a rearwardly moving trigger, a detent lever fulcrumed in the frame on a transverse axis and having a forwardly extending arm normally in movement-opposing relation to the trigger and also having a depending arm, a spring normally holding said lever with its forwardly projecting arm in movement-opposing relation to the trigger, and an upstanding lever fulcrumed near its lower end in the frame on a transverse axis and forming with said grip-forming portion of the frame the grip of the gun and movable against the depending arm of the first lever 95 to actuate the latter. 100

3. In combination, the frame having a downwardly projecting grip-forming portion, a firing mechanism including a rearwardly moving trigger, a detent lever fulcrumed in the frame on a transverse axis and having a forwardly extending arm normally in movement-opposing relation to the trigger and also having a depending arm, an upstanding lever fulcrumed near its lower end in the frame on a transverse axis and forming with said grip-forming portion of the frame the grip of the gun and bearing 110 backwardly against the frame, said depending arm of the first lever bearing backwardly against the second lever, and a spring opposing the movement of the first lever in response to forward movement of the second lever. 115

4. In combination, the frame having an 125 elongated longitudinally extending upwardly open groove, a breech-bolt having limited forward and rearward sliding movement on the frame over the groove, a firing mechanism, a magazine and its normally 130

5 elevated platform, the breech-bolt having a locking notch on its under side, and a detent lever arranged in said groove and having a bearing upon the bottom thereof, said lever having a fulcrum on the under side of the breech-bolt and being engageable, and adapted to be moved by the platform into locking engagement, with said notch and adapted to bear forwardly against the frame.

10 5. In combination, the frame having an elongated longitudinally extending upwardly open housing, a removable breech-bolt having limited forward and rearward sliding movement on the frame over the 15 housing, a firing mechanism, a magazine and its normally elevated platform, the breech-

bolt having a locking notch on its under side, and a detent lever arranged in said housing and engageable, and adapted to be moved by the platform into locking engagement, with 20 said notch, said housing having surfaces opposing longitudinal movement of the lever in the housing and converging upwardly one at an angle substantially coinciding with an arc concentric with a point in the housing 25 at or near the other of said surfaces.

In testimony whereof I affix my signature in presence of two witnesses.

CHARLES A. NELSON.
